TERMINAL AND METHOD OF MAKING IT

Robert Temple, Jr., Pittsburgh, Pa.

Application November 22, 1938, Serial No. 241,815

13 Claims. (CL 153—2)

This invention relates to a terminal or connector for an electric conductor or a strand element, and to methods for making the same.

Heretofore, it has been the practice in many electrical installations to provide electric wires, cables, or other conductors with terminal tips which facilitate electrically connecting the wire or conductor. Most of the terminals heretofore employed have been made from sheet metal stampings, metal castings or in similar ways to provide a terminal having a flat metal portion with an aperture therethrough and formed integrally with a shank portion adapted to be folded or bent around the end of an electric conductor, or having a socket portion in which the end of the conductor is received. The electric conductor is usually connected to the terminal just described by a soldering or like operation.

Terminals or connectors of the type just described have been open to the objection that in the larger sizes it is a time-consuming and laborious operation to secure the end of an electric conductor to the terminal, and this is particularly true when working with metals which are difficult to solder. Even when apparently soldered satisfactorily the electrical efficiency of the joint may be low and skilled operators are usually a requisite. Moreover, in the case of heavy electrical overloads due to shorting or as occasioned by lightning striking the conductors, the connecting solder has been melted and the terminal released from the conductor. Again, in many instances the terminals, particularly in the larger sizes, are relatively expensive to make and often require special forming dies. It is not uncommon to require a considerable variation in terminal size in a given electrical installation so that a large number of different-sized terminals must be carried in stock.

It is the general object of my invention to avoid and overcome the foregoing and other difficulties attending the provision and use of electric terminals or connectors by providing a relatively inexpensive, easily applied terminal, and in which the electric conductivity is substantially perfect, and will be maintained so despite heavy overloads.

Another object of my invention is the provision of improved methods for forming a terminal on the ends of an electric wire, cable or other conductor, and, more broadly, a connector or tip for substantially any strand element.

Another object of my invention is the provision of new and useful methods for explosively compressing a short length of tubing around the

end of an electric conductor and simultaneously punching a hole through the flattened portion so as to produce a terminal.

Another object of my invention is the provision of a terminal or connector for the end of an electric conductor or other strand element, which terminal is formed from a short length of tubing that receives the end of the conductor, the tubing being flattened at one end as is the conductor received therein, the flattened portion having a hole punched therethrough and having the sleeve and electric conductor pressed intimately together for substantially perfect electric contact.

Other objects of my invention include the provision of a terminal having means for sealing around the insulation of an insulated wire, and the provision of a terminal for connecting different metals, such as copper and aluminum.

The foregoing and other objects of my invention are achieved by the provision of a terminal, and methods and apparatus for making it, all as particularly illustrated in the accompanying drawing, wherein Fig. 1 is a plan view of a terminal embodying the principles of my invention; Fig. 2 is a side elevation of the terminal illustrated in Fig. 1; Fig. 3 is a longitudinal cross-sectional view on an enlarged scale of the terminal of Fig. 1 and taken on line III—III thereof; Fig. 4 is a transverse vertical cross-sectional view on the same scale as Fig. 3 of the terminal, this view being taken on line IV—IV of Fig. 1; Fig. 5 is a front elevation, partly in section, of my improved apparatus for forming the terminal of Figs. 1 to 4; Fig. 6 is a plan view of one of the dies shown in Fig. 5 and the holding means associated therewith, all as taken substantially on line VI—VI of Fig. 5; Fig. 7 is a side elevation of the apparatus shown in Fig. 5, but includes a slightly modified construction of the upper die; and Fig. 8 is a longitudinal sectional view of a terminal formed from a bimetallic tube.

In particularly describing my improved terminal or connector and methods and apparatus for making it as illustrated, for example, in the drawing, it should be understood that I contemplate forming a terminal on an electric conductor of substantially any type, as, for example, a solid wire, a wire cable, a bus-bar, or the like. Thus, in the specification and claims when reference is made to a wire or electric conductor, it is intended to cover any electric conductor, as, for example, of the several types specifically identified just above. Also, it might be well to note here that I contemplate forming a terminal on

wires of any of a variety of compositions which will include brass, copper, aluminum, steel, or alloys thereof, and the terminal itself can be of any of these metals.

The terminals when formed on the end of a wire can be useful not only to connect a wire into an electric circuit, but I have found also that the terminals can be used to connect wires to each other, or can be used as connectors to connect the end of a wire or cable to a given object, or to each other, and wherein the wire is not employed in an electric circuit but is used to make a mechanical or load-carrying connection. Accordingly, the words "terminal," "connector," and "wire" are intended to be broad enough when read in either the specification or claims to cover a purely mechanical or load-bearing connection instead of, or interchangeably with, an electric circuit connection.

Having particular reference to the accompanying drawing, the numeral 10 indicates as a whole an electric conductor, wire, or other strand element which has been illustrated as being formed of a plurality of strands, and including, if desired, a covering 12 of insulation. The bared end of the wire 10 is received in a short length of metal tubing 14 which has an internal bore of such a diameter as to closely receive and surround the end of the wire. The tubing 14 is preferably formed with a belled or expanded end 15 of a relatively short axial length which is adapted to receive and surround the insulation 12 on the wire 10. The belled end 15 of the tubing 14 effects a seal around the end of the insulation and prevents the entrance of moisture between the end of the insulation and the wire.

As particularly shown in Fig. 3, the ends of the wire extend substantially to the outermost end of the tubing 14 and are in fact illustrated flush therewith. The outermost half, or a somewhat greater or less length of the tubing 14, is flattened as at 16 and 17 by powerful squeezing means as hereinafter described. The flattening of the tubing serves also to flatten the end of the wire 10, as particularly shown in Figs. 3 and 4, so that the tubing and wire is compressed together in an integral or intimate manner, which provides an excellent and substantially perfect electrical contact between the tubing 14 and the wire 10.

As will be evident from Figs. 2 and 3, the flattening of the end of the tubing 14 is preferably such that the bottom or lowermost part 17 of the flattened end portion is substantially in alignment with the bottom of the unflattened end of the tubing, whereas the top 16 of the flattened end is considerably offset from the unflattened top of the tubing. As hereinafter described, my improved methods and apparatus effect this type of flattening of the tubing and wire which is desirable for the reason that the terminal can be brought into engagement with a flat surface without tilting and so that a firm, flat, electrical contact is assured.

As best shown in Fig. 4, the sides 19 of the flattened end of the terminal are formed at other than a true perpendicular and preferably are inclined slightly outwardly. This shape permits the removal of the terminal end from the forming dies as hereinafter described. The flattened end of the tubing or terminal as just described is formed with an aperture, usually round, therethrough which has been identified by the numeral 18. This aperture serves to permit the flattened end of the terminal to be con-

nected into an electric circuit by a bolt or screw, as will be understood.

Having particular reference to Figs. 5, 6 and 7, a typical apparatus for forming my improved connector or terminal comprises a frame indicated as a whole by the numeral 22, which frame includes a barrel portion 24 and an anvil 26, the latter being held in spaced relation, but in alignment, with the muzzle end of the barrel. Slidably received in barrel 24 is a piston 28 which is formed at its end with a male die member 30. The die member 30 may be screwed or otherwise secured to the end of the piston 28 so as to permit changes in size of the die member, or it can be formed integrally with the piston in the manner shown in Fig. 5.

Cooperating with the die member 30 is a female die 32 which is supported on the anvil 26. Like the die member 30 the die 32 can be made integral with the anvil 26 or can be received in a suitable recess in the anvil, as shown, so that dies of different sizes can be interchanged on the anvil. The die 32 is provided with a channel 38 adapted to receive the end of the tubing 14, as shown in dotted lines, which tubing has the wire end extending therein. I preferably position the tubing 14 and the wire 10 with relation to the die 32 and in the channel 38, and preferably accomplish this by forming the die 32 with a closed end 34 against which the end of the tubing 14 and the end of the wire 10 can abut, although this is not requisite to successful operation. Suitable means, such as a pair of spring fingers 36, secured to the anvil 26, are generally incorporated with the apparatus for centering the tubing 14 laterally of the die 32. It will be recognized that the tubing can be sprung down between the fingers 36 and will be positioned thereby centrally of the channel 38 during the flattening of the tubing end, and that the flattened tubing can be quickly released from between the spring fingers after the terminal-forming operation.

The channel or channel-shaped opening 38 provided in the die 32, which channel receives the end of the tubing, is formed with side walls which are inclined slightly outwardly so that the flattened end of the terminal can readily be removed from the die. It will be understood that the lateral distance between the sides of the channel determines the width of the flattened terminal end. The die member 30, as heretofore stated, is complementary to the channel 38 in the die opening 32, and the end of the die member 30 in the downward stroke of the piston 28 engages with the end of the tubing 14 and flattens it, and the wire therein, down against the bottom of the channel opening in the die 32 to form the flattened end on the tubing to thereby produce a terminal.

In order to punch the hole 18 through the flattened end of the terminal, I may form the die member 30 with an integral punch 40, as shown in Fig. 7, and provide the die 32 and the anvil 26 with aligned apertures 42 which receive the slug punched out of the flattened end. Preferably, I provide the piston 28 with a reciprocable weight 44 which is slidably carried in a longitudinal bore 45 in the piston and secure a punch rod 46 to the weight 44. The end of the punch rod 46 in the normal uppermost position of the weight 44 is such that the end of the punch rod 46 is flush with the bottom of the die member 30, as shown. The weight 44 is normally held

at the uppermost end of the bore 45 by a light weight compression spring 48.

The construction and arrangement of the weight 44 and punch rod 46 and associated spring 48 is such that when the piston 28 is driven downwardly to bring the die member 30 into engagement with the die 32, the end of the punch rod 46 flush with the end of the die member 30 acts to first compress and flatten the end of the tubing received between the dies. When the flattening movement of the dies together is stopped by the complete compression of the flattening portion, then the momentum of the weight 44 is such that it drives forward to force the punch rod 46 through the flattened end of the terminal to thereby punch a slug out of the aperture 42 in the die 32 and the anvil 26. This punching action commences only near the end of the flattening operation on the tube and, because of this, has been found to provide a somewhat cleaner-cut flattening and punching of the terminal end.

The operation of the punching mechanism as just described is dependent upon building up a comparatively high momentum in the piston 28 during the flattening stroke of the dies together, and, as hereinafter described, is largely dependent upon driving the piston 28 by the detonation of an explosive charge. I contemplate shortening the length of the punch rod 46 so that the lowermost end of the punch rod is some distance from the bottom end of the die 30. This construction increases the momentum and punching action of the weight 44 and punch rod 46 in the downward stroke of the piston 28 so that the punching action follows the complete flattening of the end of the tubing by the die member 30.

In order to drive the piston 28 with high velocity the end of the barrel 24 of the apparatus remote from the anvil 26 is formed with a breech and a removable breech-block and firing-pin of the type, for example, shown in my Patent No. 2,030,803, so that this portion of the apparatus, indicated as a whole by the numeral 59, will not be described in detail. Suffice it to say that the breech-block is removable so that the breech end of the barrel can receive a blank cartridge which can be detonated through a firing-pin associated with the breech-block when the breech-block is replaced over the end of the barrel.

In the operation of the apparatus shown in Figs. 5 to 7, the bared end of a wire 10 is inserted into a short length of tubing 14, and the end of the tubing and wire is abutted against the end 34 of the die 32 with the tubing and wire end being received in the channel 38 of the die. The tubing and wire end is held in properly centered relation in the channel by the spring fingers 36. The piston 28 is then pushed back up to the breech end of the barrel 24, the breech-block on the end of the barrel is removed and a blank cartridge or other suitable explosive means is inserted in the breech, and the breech-block is then replaced. Now the firing-pin is operated to detonate the explosive charge which drives the piston down through the barrel 24 of the apparatus with great speed and power and causes the die member 30 to engage with the side of the outermost end of the tubing to flatten the tubing and wire therein against the bottom of the channel 38 in the die 32. Striking the high velocity blow such as just described causes the flattening to occur substantially all on the upper side of the terminal, as will be evident from the terminal shown in Figs. 1 to 4.

5 I contemplate increasing the length of the die 32 so that the lower side of the tubing 14 is supported over substantially its full length, which prevents any offsetting in this side or bottom of the tubing.

10 If the die member 30 is formed with the integral punch 40 as shown in Fig. 7, an aperture or hole is punched through the flattened end of the tubing and through the wire in the flattened end, and this punching operation is done substantially simultaneously with the flattening of the tubing. On the other hand, in the form of my invention shown in Fig. 5, once the end of the tubing has been flattened and the downward movement of the piston 28 substantially arrested, the weight 44 continues to move forward under its own momentum to thereby drive the punch rod 46 through the flattened terminal end to provide a round hole therethrough. After the flattening and punching operation has been achieved as just described, the piston 28 is pushed back up into the barrel 24 and the terminal and wire are readily removed from between the spring fingers 36 and the die 32 and a new tubing with a wire therein is inserted into the channel 38 of the die 32, and the operation is repeated.

15 In the form of terminal shown in Fig. 8, the tubing employed is a bimetallic tubing adapted to be used to connect two different metals. Specifically, the numeral 60 indicates an aluminum wire to which the compound tube 62-64 is secured. The inner tubing 62 is aluminum whereas the outer tubing 64 is copper, although it should be expressly understood that other metals can be used to make any particular conditions. For instance, in the example given an aluminum wire is adapted to be connected to a copper bus-bar by the bimetallic terminal, having the inner tubing of aluminum engaging with the aluminum wire and the outer tubing of copper engaging with the copper bus-bar. The very high pressure used to press the terminal causes such intimate contact between the different metal parts 20 of the bimetallic tube that there is little or no electrolysis or corrosion between these parts. So far as I am aware, electrical connections between different metals, such as copper and aluminum, have always resulted in very undesirable electrolysis and corrosion. By selecting a bimetallic tube having an inner tubing of the same metal as the wire and an outer tubing of the same metal as the other member to be connected, I am able to substantially eliminate corrosion as stated above.

25 The terminal of Fig. 8 has been illustrated as having an equal offset on both its top and bottom. This is effected by shortening the die 32 so that the bimetallic tube 62-64 is supported by the die only along the bottom of that portion of the tube which is flattened as distinguished from the long die support shown in Figs. 5, 6 and 7 which results in the offset all being on the top side of the terminal.

30 I may make the dies 30 and 32 semi-circular in shape and merely compress the bimetallic tube 62-64 around the end of the wire 60 so as to provide a terminal having a round end which can be soldered into a cup or socket formed of the same material as the outside tubing 64.

35 From the foregoing it will be recognized that the objects of my invention have been achieved by the provision of an improved terminal which is readily and inexpensively made, and in which the movement of the dies together to flatten the terminal end is under the forces created by a

detonated explosive charge so that the tubing and the wire end are intimately bonded or crushed together under comparatively high forces which may be up to or even over 50,000 pounds per square inch. These forces literally flow the inner surface of the tubing and the outer surface of the wire together to thereby provide substantially perfect electrical conductivity. The terminal or connector can be made in substantially any size desired and from any of the materials heretofore indicated. The terminal can not fail in any heavy overload, and is less expensive and more easily and quickly applied than the standard cast or pressed terminal, particularly in the larger sizes. There is no heating or soldering required, and the bare wires themselves extend to the end of the terminal so that a particularly good mechanical and electrical connection is made between the wire and the tubing.

My improved apparatus operating from the power of a blank cartridge can be made relatively light and inexpensive and yet the apparatus will function over long periods of time substantially without maintenance or repair, and by substituting die sizes and shapes as described I can readily adapt my apparatus to compress terminals of a plurality of sizes. The operation of my improved press is readily mastered by the ordinary unskilled workman and operates relatively rapidly and without noise to achieve the pressing and flattening of the tubing end to form a terminal or connector. Moreover, since the terminal itself is formed from an ordinary piece of tubing, the expense thereof is kept at a minimum, and supply and stocking of various sizes is a simple matter.

While in accordance with the patent statutes I have illustrated and described specifically one particular embodiment of my invention, it should be understood that my invention is not limited thereto or thereby but is defined in the appended claims.

I claim:

1. A terminal for a wire end comprising a length of metal tubing receiving the bare end of the wire snugly within its bore, the outermost end of the tubing being substantially flush with the outermost end of the wire, said tubing and wire therein being flattened and compressed firmly together over at least one end of the tubing, and the flattened end of the tubing and wire having a hole punched therethrough.

2. A terminal or connector for the bare end of an insulated wire and comprising a short length of metal tubing receiving the bare end of the wire snugly within its bore, the outermost end of the tubing being substantially flush with the outermost end of the wire, said tubing and wire therein being flattened and compressed firmly together over at least one end of the tubing, from one side thereof to offset such portion from the unflattened wall, the side of the tubing opposite said portion being substantially in line with the unflattened wall of the tubing, the flattened end of the tubing and wire having a hole punched therethrough, and the innermost end of the metal tubing being balled to receive the end of the insulation on the wire in substantially sealing relation therewith.

3. A terminal adapted to connect a wire of one metal to a member of another metal and comprising a length of metal tubing receiving the bare end of the wire snugly within its bore, said tubing being of substantially the same material as the wire, an outer tubing of a different metal

which is substantially the same as the metal of the member to be connected, said outer tubing closely surrounding the inner tubing, the outermost ends of the tubings being substantially flush with the outermost end of the wire, said tubings and wire therein being flattened and compressed firmly together over one end of the tubings, the flattened end of the tubings and wire having a hole punched therethrough.

4. A terminal for a wire end comprising a short length of metal tubing receiving the bare end of the wire snugly within its bore, the outermost end of the tubing being substantially flush with the outermost end of the wire, said tubing and wire therein being flattened and compressed firmly together over at least one end of the tubing, the flattened end of the tubing and wire having a hole punched therethrough, the sides of the flattened end being inclined slightly outwardly relative to the bottom of the flattened end, and the bottom of the flattened end of the tubing being substantially in line with the unflattened wall of the tubing and the top of the flattened end being offset from the unflattened wall of the tubing.

5. A terminal for a wire end comprising a length of metal tubing receiving the bare end of the wire snugly within its bore, said tubing and wire therein being flattened and compressed firmly together over at least one end of the tubing, the flattened end of the tubing and wire having a hole punched therethrough, the sides of the flattened end being inclined slightly outwardly relative to the bottom of the flattened end, and the bottom of the flattened end of the tubing being substantially in line with the unflattened wall of the tubing and the top of the flattened end being offset from the unflattened wall of the tubing.

30 6. A terminal for a wire end comprising a length of metal tubing receiving the bare end of the wire snugly within its bore, said tubing and wire therein being flattened and compressed firmly together over at least one end of the tubing, the flattened end of the tubing and wire having a hole punched therethrough, the sides of the flattened end being inclined slightly outwardly relative to the bottom of the flattened end, and the bottom of the flattened end of the tubing being substantially in line with the unflattened wall of the tubing and the top of the flattened end being offset from the unflattened wall of the tubing.

35 7. A terminal for a wire end comprising a length of metal tubing receiving the bare end of the wire snugly within its bore, said tubing and wire therein being flattened and compressed firmly together over at least one end of the tubing, the flattened end of the tubing and wire having a hole punched therethrough, and the bottom of the flattened end of the tubing being substantially in line with the unflattened wall of the tubing and the top of the flattened end being offset from the unflattened wall of the tubing.

40 8. A terminal for a wire end comprising a length of metal tubing receiving the bare end of the wire snugly within its bore, said tubing and wire therein being flattened and compressed firmly together over at least one end of the tubing, the flattened end of the tubing and wire having a hole punched therethrough, and the sides of the flattened end being inclined slightly outwardly relative to the bottom of the flattened end.

45 9. A terminal for a wire end comprising a length of metal tubing receiving the bare end of the wire snugly within its bore, said tubing and wire therein being flattened and compressed firmly together over at least one end of the tubing, the flattened end of the tubing and wire having a hole punched therethrough, and the sides of the flattened end being inclined slightly outwardly relative to the bottom of the flattened end.

50 10. A terminal for a wire end comprising a length of metal tubing receiving the bare end of the wire snugly within its bore, said tubing and wire therein being flattened and compressed firmly together over at least one end of the tubing, the flattened end of the tubing and wire having a hole punched therethrough, and the sides of the flattened end being inclined slightly outwardly relative to the bottom of the flattened end.

55 11. A terminal for a wire end comprising a length of metal tubing receiving the bare end of the wire snugly within its bore, said tubing and wire therein being flattened and compressed firmly together over at least one end of the tubing, the flattened end of the tubing and wire having a hole punched therethrough, and the sides of the flattened end being inclined slightly outwardly relative to the bottom of the flattened end.

length of bimetallic tubing having an inside surface of substantially the same metal as the wire and adapted to closely receive and surround the bare end of the wire and an outside surface of substantially the same metal as the member, placing the end of the wire in the tubing so that the wire extends substantially through the tubing, flattening the outermost end of the tubing and the wire therein by means of the detonation of an explosive charge, punching a hole through the flattened end by the power of the detonation of the same explosive charge, and joining the outside surface of the terminal to the member to be connected.

10. That method of making a terminal or connector on the end of a wire which comprises providing a length of metal tubing having an inside diameter adapted to closely receive and surround the end of the wire, placing the end of the wire in the tubing, flattening the outermost end of the tubing by means of the detonation of an explosive charge, and punching a hole through the flattened end by the power of the detonation of the same explosive charge.

11. That method of making a terminal or connector on the end of a wire which comprises providing a length of metal tubing having an inside diameter adapted to closely receive and surround the end of the wire, placing the end of the wire in the tubing so that the wire extends substantially through the tubing, flattening the outer-

most end of the tubing and the wire therein by means of the detonation of an explosive charge, and simultaneously with the flattening operation punching a hole through the end of the tubing and wire by the power of the detonation of the same explosive charge.

12. That method of making a terminal or connector on the bare end of a wire which comprises providing a short length of metal tubing having an inside diameter adapted to closely receive and surround the bare end of the wire, placing the end of the wire in the tubing so that the wire extends substantially through the tubing, flattening the outermost end of the tubing and the wire therein by means of the detonation of an explosive charge, and utilizing the power of the detonation of the same explosive charge to punch a hole through the flattened end after it has been substantially completely flattened.

13. That method of making a terminal or connector on the end of a wire which comprises providing a length of metal tubing adapted to receive a wire end in its bore, placing the end of the wire in the tubing so that the wire extends substantially through the tubing and simultaneously flattening the outermost end of the tubing and the wire therein while positively confining the sides of the tubing so that the tubing in the flattened portion is of a trapezoidal cross section.

ROBERT TEMPLE, JR.
